INSULATED PICNIC COOLER

Ronald A. Wendlandt, Cincinnati, Ohio, assignor to Heck-in Can Company, Cincinnati, Ohio, a corporation of Ohio

Application July 27, 1959, Serial No. 56,954

Term of patent 14 years

(Cl. D58—17)

Fig. 1 is a perspective view showing one side of my new design for an insulated picnic cooler.

Fig. 2 is a perspective view of the opposite side of Fig. 1.

Fig. 3 is a top plan view thereof.

Fig. 4 is a bottom plan view thereof.

Fig. 5 is an enlarged sectional view through the top portion thereof taken on line 5—5 of Fig. 3.

Fig. 6 is an enlarged sectional view through the bottom portion thereof taken on line 6—6 of Fig. 4.

I claim:

The ornamental design for an insulated picnic cooler, as shown.
